UNITED STATES PATENT OFFICE.

RICHARD RONALD J. COPELAND, OF STOKE-ON-TRENT, ENGLAND, ASSIGNOR TO COPELAND & THOMPSON, INC., OF NEW YORK, N. Y., A CORPORATION OF NEW YORK.

DESIGN FOR A PLATE OR SIMILAR ARTICLE.

Application filed September 28, 1928. Serial No. 28,318. Term of patent 14 years.

To all whom it may concern:

Be it known that I, RICHARD RONALD J. COPELAND, a subject of the King of Great Britain, and a resident of Stoke-on-Trent, Staffordshire, England, have invented a new, original, and ornamental Design for Plates or Similar Articles, of which the following is a specification, reference being had to the ac-

companying drawing, forming a part thereof.

The single figure of the drawing is a plan view of a plate showing my new design.

I claim:

The ornamental design for a plate or similar article, as shown.

R. RONALD J. COPELAND.
